UNITED STATES PATENT OFFICE.

CHARLES M. KOLBENSTETTER AND CHARLES W. STAUFFIGER, OF DETROIT,
MICHIGAN, ASSIGNORS TO KOL-BEN WHEEL COMPANY, OF DETROIT, MICH-
IGAN, A CORPORATION OF MICHIGAN.

DEMOUNTABLE WHEEL.

1,357,997.

Specification of Letters Patent.

Patented Nov. 9, 1920.

Application filed December 13, 1917. Serial No. 206,888.

To all whom it may concern:

Be it known that we, CHARLES M. KOLBENSTETTER and CHARLES W. STAUFFIGER, citizens of the United States of America, residing at Detroit, in the county of Wayne and State of Michigan, have invented certain new and useful Improvements in Demountable Wheels, of which the following is a specification, reference being had therein to the accompanying drawings.

This invention relates to a hub construction for demountable wheels and its object is to provide simple and efficient means for detachably and demountably securing the wheel in place, whereby it is firmly held against movement relative to an inner hub member and locked in place against any possibility of accidental displacement, and further, whereby the demountable member is forced to place upon the inner member by the securing means and forcibly disconnected therefrom by the operation of the securing means in operating the same to detach the wheel. A further object is to provide a construction whereby many of the parts may be formed of sheet metal stampings, thus insuring accuracy, cheapness, strength and durability, and to provide certain other new and useful features in the construction, arrangement and combination of parts, all as hereinafter more fully described.

With these and other ends in view, the invention consists in the matters hereinafter set forth and more particularly pointed out in the appended claims, reference being had to the accompanying drawings, in which—

Figure 1 is illustrative of a hub construction embodying the invention, in which a demountable or outer member of the hub is shown in longitudinal vertical section, and an inner or fixed member, in side elevation;

Fig. 2 is a sectional side elevation of the same with the section taken substantially upon the line II—II of Fig. 1;

Fig. 3 is a detail view of the outer end portion of the hub, showing parts thereof in section;

Fig. 4 is a perspective view of a locking cap detached;

Fig. 5, an end elevation of the same;

Fig. 6, a side elevation of the outer end portion of the inner fixed member;

Fig. 7 is a transverse section of Fig. 1 substantially upon the line VII—VII;

Fig. 8 is a detail showing a portion of a retaining ring in elevation;

Fig. 9 is a sectional view similar to that of Fig. 1, and illustrating a modification of the construction; and

Fig. 10 is an elevation of the same with parts removed and others broken away and in section to more fully disclose the construction.

The construction shown in Figs. 1 and 2, is particularly adapted to wire wheels but it will be understood that by slight changes, the same may be applied to wheels having wooden spokes, or the artillery type of wheel, and further, the construction disclosed in Figs. 9 and 10 may be modified to adapt the same for use on wire wheels instead of the artillery type, as shown. Obviously, changes may be made in the size, proportion, arrangement and construction of parts without departing from the spirit of the invention, and all within the scope of the appended claims.

As shown in Fig. 1, 1 indicates the cylindrical or supporting portion of an inner member of the wheel hub which member is adapted to be attached to an axle shaft or to turn upon an axle skein in the usual manner of applying the driving or the front wheels to a motor vehicle, said member being designed to remain in place upon the axle when the outer or demountable sleeve 2 of the hub which is adapted to fit snugly thereover, is removed for the purpose of demounting the wheel. An outstanding flange 3 on the inner or fixed member is provided to oppose a like flange 4 on the demountable hub, said cylindrical part 2 and flange 4 being preferably formed from a single sheet or piece for the purposes of cheapness and lightness of construction. An outer cup-shaped shell 5 also preferably formed of sheet metal has a cylindrical end portion 6 to fit closely over the outer end of the sleeve 2 and project beyond the end thereof, said shell being secured by rivets or otherwise, to the flange 4 near its outer edge, said members thus forming a hollow body or outer hub to which the spokes 7 are secured by passing the same through holes provided therefor in the pro-

jecting end portion 6 and in a flange 8 on the shell turned inwardly over the periphery of the flange 4.

The outer end of the inner or fixed hub is reduced in diameter as at 9 and this reduced end portion is formed with radial lugs 10 at opposite sides thereof for the engagement therewith of ribs or inwardly bent portions 11 upon a locking cap 12, the cap being of a diameter to fit loosely within the projecting end portion 6 of the shell and the portions 11 which lie at opposite sides of the cap, being formed by cutting or severing the metal of the rim of the cap at a distance 15 from its edge and along a line extending at an inclination to said edge, and then bending inwardly the portions thus partially severed from the cap. These indent portions thus form internal ribs each having a sharply defined side edge 13 which is inclined to the plane of rotation of the cap, to engage behind the lugs 10 when the cap is slipped upon the end portion 9 and rotated; the lugs being also formed with inner 25 sides likewise inclined so that the cap will be moved endwise and by the engagement of its inner rim or edge with the outer ends of the sleeve 2, force the entire outer or demountable hub into place and lock it upon the inner member or hub. A reverse turning movement of the cap brings those portions 11 of the cap out of alignment with the lugs and by providing a cam projection 14 on the shoulder 15 formed by the reduced 30 end 9 on the inner hub member, and also providing a lug 16 on the interior of the cap, properly positioned relative to the inclines 13 thereon, when the cap is turned to release the wheel, this lug 16 will come 35 into contact with the cam projection 14 after the cap has been turned backwardly, or counterclockwise a short distance and force the cap longitudinally outward or away from the shoulder 15, which movement of the cap will move the outer or demountable hub longitudinally upon the inner member or cylindrical portion 1, due to the fact that said cap is attached to or held within the outer projecting end portion 6 40 of the shell 5 by a retaining ring 17 having screw threaded engagement with said end portion and being provided with an inwardly extending flange 18 to engage the cap and prevent its withdrawal from the shell. The cap may however be turned 45 within the ring by means of a suitable tool or wrench (not shown) applied to an angularly shaped end portion 19 on the cap which projects through and beyond the ring, but this turning movement is preferably 50 limited by providing a lug 45 projecting from the end edge of the cap to engage an elongated notch 46 cut in the end of the wall of the tubular portion 2 of the demountable 55 hub.

The retaining ring 17 is securely locked upon the shell against accidental displacement or turning, by a set screw 20 having a reduced end portion 21 passing through an opening in the wall of the shell, and this same set screw 20 also serves to lock the cap in any position to which it is turned, by screwing the set screw inwardly, bringing its reduced end 21 into contact with the rim of the cap. Where the cap is turned to 75 locked position in engagement with the lugs 10, to force the demountable member upon and hold it firmly in place upon the inner hub member, said cap may be locked by the set screw against accidental 80 turning relative to the demountable member and thus all possibility of the wheel becoming loose or coming off is obviated. To prevent this set screw from coming out of its screwthreaded hole in the ring, after the 85 screw is inserted therein, the metal at the extreme outer end of the hole is peened inwardly as at 22.

The demountable hub member is prevented from turning upon the inner hub 90 member by providing the sleeve portion 2 with an inwardly projecting rib or key 23 which is tapered longitudinally its sides diverging toward the outer end of the hub, and the cylindrical portion 1 of the fixed or 95 inner hub member is formed with a groove or slot 24 the sides of which diverge in a like manner, thus providing a tapered seat for the key, which when the demountable member is forced longitudinally upon the 100 inner member, will seat firmly in the keyway 24, and obviate any possibility of relative turning between the inner and outer hub members. The tapered key also provides for wear of the parts and when the 105 demountable member is released by the backward turning of the locking cap 12, will readily release itself from its seat, thus insuring the ready removal of the demountable wheel. 110

A very strong, cheap and durable construction is provided by forming the locking cap 12 with the locking portions 11 struck out from the body which is formed of sheet metal, and a minimum number of 115 parts is required, the cap performing the double function of a cap to close the outer end of the shell and to lock the parts together.

In the modified construction shown in 120 Figs. 9 and 10, the inner or fixed member comprises a body or barrel having an inner cylindrical portion 25 and an outer end portion 26 of lesser diameter with a channel or groove 27 in the body between the two portions, the outer side wall 28 of said groove being inclined. At the inner end of the portion 25 is a flange 29 to oppose a ring plate 30, between which and a flange 31 on the sleeve 32, are secured the spokes 33 of the 125 130

demountable wheel. The sleeve 32 fits upon the portion 25 of the inner hub or body and this portion is formed with a tapering slot or groove 34 to receive a rib or key 35 on 5 the sleeve 32.

The outer or demountable hub is secured upon the inner hub or barrel with the key 35 firmly seated in its groove 34, by means of two wedge members 36 slidable within 10 grooves 37 formed radially of the axis of rotation of the wheel within the outer face of the flange 31 and the inner face of the flange 38 of a rotatable locking cap 39 formed to fit loosely over the outer end portion 26 of the inner barrel and preferably 15 made hexagonal in cross-section or with facets so that a wrench may be applied thereto for turning the same. A recessed retaining ring 40 is secured near its periphery 20 against the outer face of the flange 31 by means of bolts 41 which also serve to secure said flange and plate 30 together with the spokes between them. The inner portion 25 of the retaining ring 40 is offset or recessed 25 to receive the flange 38 of the cap and to overlie the same to form a centering guide therefor and retain the same in place upon the demountable or outer hub at the same time permitting of free rotation of the 30 locking cap. The wedge members or dogs 36 are tapered at the inner ends to engage the tapered or slanting side 28 of the groove 27 and these dogs are moved radially into and out of said groove by means of a pin 35 42 secured to each dog and provided with a head to engage slots 43 in the flange 38 of the locking cap, said slots being formed eccentric to the axis of rotation of said cap so that when said cap is rotated in one 40 direction, the slots, by reason of such eccentricity, will force the pins and hence the dogs, to move radially outward as the flange of the caps in which the slots are formed, is turned relative to the pins. This movement 45 lifts the dogs out of the groove 27, thus releasing the outer hub so that the wheel may be dismounted from the inner or fixed hub. A reverse rotation of the locking cap will in a like manner force the dogs or wedges inwardly and by the engagement of their inner 50 beveled ends with the inclined side of the groove, move the demountable wheel longitudinally inward upon the inner hub to firmly seat the key 35 in its groove 34 and 55 securely lock the inner and outer hubs together against relative turning in either direction.

To form a finish for the hub and inclose all of the movable parts, making the hub 60 dust and oil tight, an outer shell or cap 44, formed of thin sheet metal is shaped to fit upon the hexagonal portion 39 of the locking cap and extend outwardly with its rim fitting snugly over the outer edge of the retaining ring 40.

By the simple application of a wrench to the faceted portion of the shell 44 and the turning of the retaining or locking cap 39 thereby, the wheel may be very quickly and easily unlocked and demounted from the inner or fixed hub, thus greatly facilitating the work of changing wheels.

What we claim is:

1. In combination an inner hub member, an outer demountable hub member adapted for telescopic and non-rotative relation therewith, a locking cap member insertible within the end of the outer hub member and over the outer end of the inner hub member, radial lugs on opposite sides of 75 said outer end of the inner hub member, the locking cap being formed with internal ribs adapted to engage behind the said lugs upon rotation in one direction to draw the hubs together, means for holding the cap within the outer hub member, and a cam projection on the inner hub engaged by a portion of the cap subsequent to disengagement of the said lug engaging portions of the cap and hub.

2. In combination an inner hub member, an outer demountable member adapted for telescopic and non-rotative relation therewith, the outer end of the inner hub member being reduced providing a shoulder, radial 90 lugs on opposite sides of the outer end of the inner hub member, a locking cap insertible within the end of the outer hub member and over the reduced end of the hub member, means preventing withdrawal of the 95 cap member from the outer hub member, the cap member being provided with portions engaging the said lugs, a cam projection on the said shoulder of the inner hub member, means on the cap member to engage the same, turning of the cap member in one direction causing engagement with the said lugs and drawing the inner hub member within the outer hub member and reverse rotation to position with the portions of the cap member out of alignment with the lugs bringing a portion of the cap member into engagement with the cam projection to draw the outer hub member from 100 the inner hub member.

3. In combination an inner hub member, an outer demountable hub member adapted for telescopic and non-rotative relation therewith, a cap member insertible within the end of the outer hub member and over the outer end of the inner hub member, radial lugs on the said outer end of the inner member positioned on opposite sides, the cap member having internal projecting 110 portions adapted to engage behind the said lugs upon rotation in one direction, a ring member engaging over the end of the outer hub member and holding the cap member therewithin, rotation in one direction causing 115 the engagement of the internal project-

ing portions with the lugs to force the outer hub over the inner hub, and means on the inner hub engaged by the cap upon reverse movement to position where the internally projecting portions of the cap are out of engagement with the lugs for forcing the outer hub member off from the inner hub member.

4. In combination an inner hub member,
10 an outer demountable hub member adapted
for telescopic and non-rotative relation
therewith, a cap member insertible within
the end of the outer hub member and over
the outer end of the inner hub member, lugs
15 on opposite sides of the outer end of the inner
hub member each having an inclined
inner face, the inner end of the cap being
shaped to be inserted over the hub and lugs
and formed with parts to engage behind
20 the lugs upon turning the cap in one direc-

tion, a ring member secured to the outer end
of the outer hub and engaging over the cap
member preventing its withdrawal, the turning
of the cap member in one direction
drawing the hub members longitudinally 25
one of the other to locking relation, releasable
means for preventing turning of the cap
member, a cam lug on the inner hub member
between the said inclined lugs thereon, and
a lug on the cap member adapted to engage 30
the cam lug subsequent to disengagement
of the said lugs of the cap and hub.

In testimony whereof we affix our signatures
in presence of two witnesses.
